(Cl. 94—50)

This invention relates to road rollers of the well known class comprising a front roller unit which is adjustable for steering and hind rollers arranged on either side of the front roller unit and which constitute the driving wheels.

With such road rollers, a desirable feature is that the pressure per unit of width exerted on the ground by both the front and hind wheels respectively should be as nearly as possible equal. In order however that the roller may be capable of negotiating hills, that is to say, that the driving wheels should be capable of obtaining sufficient grip on the road surface to allow the machine to pass up inclines, it is necessary so to construct the machine that about two-thirds of the total weight thereof comes on the hind or driving wheels. In present day machines it has not been possible to combine this feature with even an approximate equality of unit pressure on the driving and steering wheels respectively. In other words with machines as at present constructed, uniform distribution of compressive power which is desirable for obtaining the smooth finish of a road, is not compatible with the best hill climbing ability.

The object of the present invention is to provide means whereby the distribution of weight between the front and hind wheels may be varied at will without the necessity of attaching or detaching any ballast weights at the time the variation is desired.

According to this invention, in a road roller comprising a front roller unit, by which the roller is steered and hind driving rollers arranged on either side of the front roller unit, there is provided a ballast weight which is movably suspended on the frame or chassis so as to be capable of adjustment from a position within the wheel or roller base to one which is in alignment with or beyond the hind axle and so arranged that its position can be varied either automatically or through suitable mechanical means to obtain either an even distribution of weight upon the said wheels or a greater or lesser weight upon the driving or steering wheels.

Preferably the ballast weight is mounted between the side members of the roller frame, and is capable of movement by means of a rope and rotatable drum mechanism means being provided for locking the weight in a predetermined position.

The ballast weight may be in a single piece or formed in several sections suitably secured together and may be mounted on wheels or rollers to reduce the effort required to move the ballast weight.

The invention is illustrated in the accompanying drawings, as applied to a motor driven road roller, but it may be applicable to steam rollers.

Figure 1 shows in vertical section the ballast

weight, mounted on the side members of the roller frame, only a portion of the frame being shown.

Figure 2 is a plan view of the mechanism according to the invention, Figure 3 being a vertical section on the line III—III Figure 2. Figure 4 is a detailed front elevational view of the bearing and bearing spindle for operating mechanical means for moving the weight, and

Figure 5 is a detailed side elevational view of the parts shown in Figure 4.

Referring to the drawings, the road roller comprises a chassis frame indicated generally at A having the usual front roller B and hind rollers C constituting the driving rollers and arranged to rotate in paths on either side of that followed by the main roller. The front roller B, by which the machine is steered is suspended from a sub-frame D itself mounted to oscillate about a fore and aft axis in a cradle E carried by the steering post F.

According to this invention a road roller, such as described, is provided with a ballast weight I so that the distribution of the weight as between the front roller and hind driving rollers can be varied as required to suit conditions. The ballast weight I is adjustably carried on the chassis frame so as to be movable from a position within the wheel base to one which may be immediately below and where it is in alignment with the hind roller axle. Preferably provision is made for the weight to be movable to a position beyond the hind axle. The channel section members 2 which form part of the chassis frame provide suitable guides or a trackway for the ballast weight. Attached to the members 2 are cover plates for the protection of the engine and other parts. The ballast weight is, preferably as shown, supported on axles 3 provided with rollers 4 which run on the inturned flanges 5 of the beams 2.

Anchored to the weight I is a rope 6, e. g., a wire rope or cable which winds on a winding drum 7 carried on a spindle 8 capable of revolving in bearings 9, 10, said spindle being rotated by means of an operating element comprising a crank handle 11 which is remote from any of a number of different positions of the ballast component on the trackway and which is here shown as detachable. The bearings 9, 10, are respectively on plates 9a, 10a secured to the members 2 by bolts 17 and (referring to Figure 5) the bearing 10 is split as indicated at 10' and is also partially separated as indicated at 10² from the plate 10a, so that the bearing 10 is free to be contracted and this is effected by a clamping screw 12 by manipulation of which the split bearing 10 can be contracted on to the spindle 8 and hold the spindle against rotation when the weight has been moved to the desired position, hence securing the weight. At the end of the roller

frame remote from the rope drum, a pulley 13 is provided around which the rope passes to be anchored at this other end to the weight 1. The pulley 13 is carried on an adjustable mounting 14 so that any slackness in the rope may be taken up. In order to prevent the weight 1 from rattling owing to vibration when the roller is in operation, the weight is provided at both sides with inclined faces 15, adjustable screws 16 being provided in the flanges 5 of the roller frame so that when the weight is moved to either end of the roller frame the appropriate pair of screws may be adjusted to bear on the inclined faces of the weight and so cause it to be wedged tightly in the frame. It will be appreciated that gearing, other than that illustrated, may be employed for moving the weight.

Instead of moving the weight by mechanical means, the arrangement may be such that the weight moves automatically under gravity when the machine is on an incline, suitable means in this case being provided to check the movement of the weight.

In use, when finishing a road the weight will be moved towards the steering wheels, equalising as far as possible the weight per unit of width on the machine wheels, whilst when greater weight is needed on the driving wheels, as for example when climbing hills or when operating a scarifier, the ballast weight will be moved in the frame towards the driving wheels.

What I claim is:

1. A road roller comprising in combination a frame, a front steering roller component connected to the frame, a hind driving roller component connected to the frame the said frame being formed with guides extending longitudinally of the roller, a ballast weight movably supported by said guides, a cable connected to the ballast weight, a rotatable drum to which the cable is connected, means to rotate the drum to move the ballast weight longitudinally to change the distribution of weight on the two roller components, and means to lock the drum against rotation.

2. A road roller comprising in combination a frame, a front steering roller component connected to the frame, a hind driving roller component connected to the frame the said frame being formed with guides extending longitudinally of the roller, a ballast weight movably supported by said guides, a cable connected to the ballast weight, a rotatable drum to which the cable is connected, means to rotate the drum to move the ballast weight longitudinally to change the distribution of weight on the two roller components, and means to lock the weight against movement.

3. A road roller comprising in combination a frame, a front steering roller component connected to the frame, a hind driving roller component connected to the frame the said frame being formed with guides extending longitudinally of the roller, a ballast weight movably supported by said guides, a cable connected to the ballast weight, a rotatable drum to which the cable is connected, means to rotate the drum to move the ballast weight longitudinally to change the distribution of weight on the two roller components, and means to lock the weight against

movement, the said means comprising screw operated devices to engage sloping faces formed on the weight.

4. A road roller comprising a frame, a front roller, means supporting said front roller from the frame for steering movement, hind driving rollers, means supporting the said hind driving rollers from the frame and at each side of the front roller, a longitudinal guide on the frame and extending from a position within the wheel base of the roller at least to one of alignment with the hind rollers, a ballast component which is movable on and supported by the guide, and means to hold the component in a selected position on the guide.

5. A road roller comprising a frame, a front roller, means supporting said front roller from the frame for steering movement, hind driving rollers, means supporting the said hind driving rollers from the frame and at each side of the front rollers, a longitudinal guide on the frame and extending from a position within the wheel base of the roller at least to one of alignment with the hind roller, a ballast component which is movable on and supported by said guide, means operatively connected to said component and being adapted for manual operation for moving the component on said guide to vary the distribution of weight on the front and rear rollers, and means to secure the component in the position to which it is moved.

6. A road roller comprising a frame, a front roller means, a hind roller means, means mounting said front and hind roller means on the frame, said frame having a trackway extending fore and aft of the frame, a ballast component mounted for free fore-and-aft movement on the trackway; and means for shifting said component fore-and-aft on said trackway including an operating element remote from said component in any of a number of different positions of the latter, and means extending longitudinally of said trackway and connecting said operating element to said component.

7. A road roller comprising a frame, a front roller means, a hind roller means, means mounting said front and hind roller means on the frame, said frame having a trackway extending fore and aft of the frame, a ballast component mounted for free fore-and-aft movement on the trackway, and means for shifting said component fore-and-aft on said trackway including an operating element mounted on said frame in fixed position longitudinally thereof, and a connection between said operating element and said component.

8. A road roller comprising a frame, a front roller means, a hind roller means, means mounting said front and hind roller means on the frame, said frame having a trackway extending fore and aft of the frame, a ballast component mounted for free fore-and-aft movement on the trackway, and means for shifting said component fore-and-aft on said trackway including a winding member journaled on the frame, a pulley journaled on the frame and longitudinally spaced from said winding member, and a cable connected to said component and being trained around said pulley and winding device.

WILLIAM HENRY BRAMBLE.
